Primary Examiner—Melody N. Brown

(74) Attorney, Agent, or Firm—Joel D. Voelzke

(57) **CLAIM**

The ornamental design for a decorative design for an automobile hood, as shown and described.

DESCRIPTION

FIG. 1 is a perspective view looking from the left front of a decorative design for an automobile hood showing my new design;

FIG. 2 is a top plan view; and,

FIG. 3 is a perspective view looking from the left rear. The bottom view is omitted and is not part of the claimed design.
